UNITED STATES PATENT OFFICE.

HERMAN PRIES AND JOHN W. MEYER, OF MICHIGAN CITY, INDIANA.

DUMP-CAR.

1,116,731.

Specification of Letters Patent.

Patented Nov. 10, 1914.

Application filed March 9, 1914. Serial No. 823,426.

To all whom it may concern:

Be it known that we, HERMAN PRIES and JOHN W. MEYER, citizens of the United States, and residents of Michigan City, county of Laporte, and State of Indiana, have invented certain new and useful Improvements in Dump-Cars, of which the following is a specification and which are illustrated in the accompanying drawings, forming a part thereof.

The invention relates to that type of dump cars which are provided with discharging doors hinged so as to open downwardly, and its object is to provide improved means for closing the door and particularly for holding the door in closed position.

In its broader aspect the invention comprises flexible means actuated by a controlling shaft for closing the door, such means embodying a hook engageable with the shaft for holding the door in closed position and supporting the weight of the load resting upon it.

The invention consists further in various details of construction all as hereinafter described.

In the accompanying drawings illustrating the invention, Figure 1 is a transverse vertical sectional detail of a car, the discharging door being shown by solid lines in closed position and by dotted lines in its open position; Fig. 2 is a detail side elevation of the car showing the door in closed position, some of the parts being omitted for the sake of clearness; and Figs. 3 and 4 are details of the door holding mechanism shown in different positions.

There is represented at 10 one of the center sills of a car; at 11 one of its transverse sills; at 12 its floor and at 13 its side wall.

In the construction as illustrated the discharge doors, one of which is represented at 14, are hinged, as shown at 15, adjacent to the center sill and close against the outer frame work of the car. These doors are controlled by a shaft 16 journaled longitudinally of the car in suitable bearings, as 17, 18, here shown as mounted upon the outer ends of the transverse sills though the precise location of the shaft is not of the essence of the invention and it may be carried by any portion of the outer framing of the car. This shaft may be of sufficient length to coöperate with a plurality of doors, as shown. Mounted upon the shaft and for

coöoperating with each of the doors there is a pair of drums 19, 20, each being preferably provided with a spiral groove 21. A chain 22 is attached at one end to each of the drums, as shown at 23, and at its other end to the outer edge of the door as represented at 24. A suitable rest, as 25, may be provided to support the door when in open position and the chain is of such length that it will permit the door to drop thereto. The shaft 16 is manually turned by means of a lever 26 swiveled upon one of its ends and carrying a reversible pawl 27 which coöperates with a ratchet wheel 28 fixed upon the shaft, a holding pawl 29 being provided to prevent the shaft from turning as the lever is moved backwardly. The lever 26 comprises a short socketed member as shown and a removable bar 30 adapted to be inserted within the socket. The last or outer element 31 of the chain 22 is in the form of a hook pivotally attached to the door and adapted to engage the shaft 16 when the door is closed and thereby support the weight of the door and the load resting upon it, relieving the ratchet mechanism from this duty.

In order that the hook may have a firm bearing upon the shaft and be freed from a tendency to slip from it, the shaft is squared at the end of the drum and the nose of the hook is provided with a flat face as shown at 32. A radial lug 33 on the drum 19 engages the arm 34 projecting laterally from the nose of the hook as the door approaches a closed position, forcing the hook outwardly so that it will clear the shaft in its upward movement. A finger 35 formed on the drum thereupon engages the rearward side of the arm 34 and forces the nose of the hook forwardly over the shaft. As illustrated, the laterally projecting arm 34 is in the form of a loop and serves the further purpose of attaching the last link (proper) of the chain to the hook element. The door being thus brought to the closed position the load is supported directly by the hook, dependence being no longer placed upon the retaining pawl, the finger in itself constituting means for preventing the hook from being disengaged from the shaft so long as the latter is locked against rotation. When it is desired to discharge the load, the pawl 29 is thrown back out of engagement with the ratchet wheel 28, the pawl 27 is reversed, and the lever being now actuated the shaft

is turned in the opposite direction, the lug 33 bearing outwardly against the arm 34, and forcing the hook 31 from the shaft whereupon the door drops to the rest 25 under the influence of the load.

We claim as our invention,—

1. In a dump car, in combination, a downwardly swinging door, a shaft having a flat side, and being located above the plane of the door when in closed position, a hook attached to the door and having a flat faced nose engageable with the flat face of the shaft, and a chain attached to the shaft and to the hook.
- 15 2. A downwardly swinging door, a shaft, a chain connecting the shaft with the door, the element of the chain adjacent the door being a hook adapted to take over the shaft, and a deflecting lug on the shaft engageable with the nose of the hook on its approach to the shaft.
- 20 3. A downwardly swinging door, a shaft, a chain connecting the shaft with the door, the element of the chain adjacent the door being a hook adapted to take over the shaft, and a finger carried by the shaft and engageable back of an appurtenance of the hook for forcing the nose of the hook over the shaft.
- 25 4. A downwardly swinging door, a shaft, a chain connecting the shaft with the door, the element of the chain adjacent the door

being a hook adapted to take over the shaft, and means for deflecting the hook from the shaft on its approach thereto.

5. A downwardly swinging door, a shaft, a chain connecting the shaft with the door, the element of the chain adjacent the door being a hook adapted to take over the shaft, a lateral projection on the hook, and projections on the shaft for engaging the front and rear faces of the lateral projection as the hook approaches the shaft.

6. A downwardly swinging door, a shaft, a hook carried by the door and adapted to take over the shaft and having a lateral projection, a finger carried by the shaft and engageable with the rear face of the projection and means for locking the shaft against rotation.

7. A downwardly swinging door, a shaft, a hook carried by the door and adapted to take over the shaft, and having a lateral projection, projections on the shaft between which the projection on the hook enters, means for locking the shaft and means for rotating the shaft.

HERMAN PRIES.
JOHN W. MEYER.
